UNITED STATES PATENT OFFICE

155,099

DESIGN FOR A MACHINE FOR SHAPING SHOULDER PADS OR THE LIKE

Bert Mechur and Walter Riedler, New York, N. Y.

Application July 26, 1947, Serial No. 140,551

Term of patent 14 years

(Cl. D49—6)

To all whom it may concern:

Be it known that we, Bert Mechur and Walter Riedler, respectively citizens of the United States and residents respectively of the city, county, and State of New York, and the city of New York, county of the Bronx, State of New York, have invented a new, original, and ornamental Design for a Machine for Shaping Shoulder Pads or the like, of which the following is a specification, reference being had to the accompanying drawing, forming part thereof, in which:

Fig. 1 is a plan view of a machine for shaping shoulder pads or the like embodying our design;

Fig. 2 is a front elevation of the same;
Fig. 3 is an end elevation of the same;
Fig. 4 is a bottom view of the same;
Fig. 5 is a front elevation of the same in exploded position; and
Fig. 6 is a similar view in end elevation.

We claim:

The ornamental design for a machine for shaping shoulder pads or the like, as shown.

BERT MECHUR.
WALTER RIEDLER.
